UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

SPEED-CONTROLLING APPARATUS FOR RAILWAY-VEHICLES.

1,325,328.

Specification of Letters Patent.

Patented Dec. 16, 1919.

Application filed March 12, 1915, Serial No. 13,853. Renewed January 11, 1919. Serial No. 270,749.

To all whom it may concern:

Be it known that I, LLOYD V. LEWIS, a citizen of the United States, residing at Edgewood Borough, in the county of Allegheny and State of Pennsylvania, have invented certain new and useful Improvements in Speed-Controlling Apparatus for Railway-Vehicles, of which the following is a specification.

10 My invention relates to speed controlling apparatus for railway vehicles.

I will describe several forms of apparatus embodying my invention and will then point out the novel features thereof in claims.

15 In the drawings, Figure 1 is a sectional view of part of one form of apparatus embodying my invention. Fig. 2 is a view of another part of one form of apparatus embodying my invention. Figs. 2^A, 2^B and 2^C

20 are views showing part of the apparatus shown in Fig. 2 in three positions. Fig. 3 is a diagrammatic view of a railway track having applied thereto one form of apparatus adapted to be used with apparatus embodying my invention. Fig. 4 shows a

25 modification of the apparatus shown in Fig. 3. Fig. 5 shows a modification of the apparatus shown in Fig. 2. Fig. 6 is a view, partly diagrammatic, of another form of

30 part of the apparatus embodying my invention. Fig. 7 is a diagrammatic view of one form of apparatus embodying my invention applied to a railway track. Fig. 8 is a view showing a modification of the apparatus

35 shown in Fig. 7. Fig. 9 is a view showing a modification of the apparatus shown in Fig. 6.

Similar reference characters refer to similar parts in each of the several views.

40 Referring first to Figs. 1 and 2, I have here shown one rail 1 of a railway track on which a train or vehicle V is adapted to travel. In order to prevent unnecessary complication of the drawing, I have shown

45 only one wheel 2 of the train or vehicle, in rolling contact with rail 1. Mounted on the train or vehicle is a casing 3 having a cover plate 8, which casing incloses a centrifugal governor 4, here shown to be of the ordinary fly-ball type, although I do not limit myself to this particular type of governor.

50 Fixed to the shaft 5 of this governor outside of the plate 8 is a pinion 5^a which is operatively connected to one of the wheels

of train or vehicle V by means of power 55 transmission mechanism of any suitable type, so that the governor is made to rotate at a speed always proportional to the speed of the train or vehicle. Shaft 5 revolves in a ball bearing 6 located in cover plate 8 and 60 in a ball bearing 7 located in casing 3. Spider arms 9, radially extending from shaft 5 carry at their extremities bell cranks 10 connected to them by means of pins 11. One arm 12 of each bell crank carries at its 65 extremity a weight 14. The other arm 13 of each bell crank extends into a slot 15 in the shaft 5. In slot 15 there is located a shaft 16, which carries two annular shoulders 31 and 32, between which the ball shaped ends 70 of arms 13 of bell cranks 10 are inserted. The left end of shaft 16 is carried in a hole 16^a in shaft 5, while the other end of shaft 16 carries the outer ring 17 of a thrust ball bearing 18. The inner ring 19 of this bearing is fixed to the left extremity of a shaft 20, which is adapted to slide longitudinally in a hole 21 through the head of casing 3. Near its right end shaft 20 is threaded, and screwed over this threaded portion is a nut 80 22 which is locked in position by a lock nut 23. The right extremity of shaft 20 is guided in a hole 25 in a plate 26. This plate 26 reciprocates in a hole 28 through a plate 29 forming a part of casing 3. The shaft 20 85 is guided near its left extremity by means of a bushing 24 fixed in casing 3. A stud 33 in shaft 5 is provided as a stop for shaft 16 when the governor 4 is at rest. When the governor revolves, the centrifugal force of 90 the weights 14 is transmitted by means of bell cranks 10 to act as a thrust on bearing 18. This force is transmitted by shaft 20 and nut 22 to plate 26, which bears against a diaphragm 341. This diaphragm will 95 yield unless resisted by an equal or greater force on its other side. I set up this resisting force in the following manner.

An air-tight cylinder 34 closed at one end by means of a head 38 is clamped at its open 100 end to the plate 29, so that the axis of the cylinder coincides with the center line of shafts 5 and 20. This cylinder is provided with two pistons 35 and 36, the former of which may be comparatively loose in the 105 cylinder so that air can pass the same and act directly on the diaphragm 341. A spring 37 is provided to hold these pistons apart, so

that piston 35 bears against diaphragm 341 and piston 36 bears against cylinder head 38. Air pressure from sources to be pointed out later may be applied through ports 39 and 40. By this means I am enabled to oppose or overcome the force exerted by the action of the centrifuge on diaphragm 341. When no air pressure is applied through ports 39 and 40, the spring alone resists the force due to the centrifuge. When air pressure is applied through port 40, the piston 36 is pushed up against stop 41, which is cushioned with an annular gasket 42, and thereby spring 37 is compressed, pushing piston 35 against the diaphragm 341 with a force greater than before. Consequently, the centrifuge 4 may be rotated at a greater speed before it overcomes the force opposing it at the diaphragm. Now, if air at substantially the same pressure is admitted through port 39, piston 36 is forced back against the cylinder head 38, due to the combined action of air pressure plus spring pressure on the left of piston 36. But the force against diaphragm 341 is now greater than before, because the air pressure acting directly against the diaphragm more than offsets the decrease in spring pressure caused by allowing the spring to expand. Consequently the centrifuge 4 may be rotated at a still greater speed before the force exerted on diaphragm 341 by plate 26 exceeds the force exerted on the diaphragm by the opposing air pressure on piston 35.

In every case, as long as the force exerted on the diaphragm due to the action of the centrifuge is less than the resisting force, plate 26 is held against face 43 of plate 29. When the centrifugal force transmitted to the diaphragm overcomes the resisting force, the diaphragm yields and pushes piston 35 against stop 41.

My device may of course be utilized in many different ways to control any desired apparatus on the vehicle; as here shown I use it to control the fluid pressure brakes in the following manner.

An arm 45 fulcrumed in casing 3 by a pin 27 is pivoted to shaft 20 by means of a pin 50. The valve stem 49 of a pin valve 44 is operatively attached to arm 45, so that, when the shaft 20 moves to the right, valve 44, which is normally closed by means of a spring 48, is opened allowing air pressure to exhaust from pipe 50 through a port 47. Pipe 50 leads to a brake application valve located on the vehicle, which brake application valve may be of any suitable type. Suffice it to point out, that when pipe 50 is opened to atmosphere by valve 44 the brakes of the vehicle are applied, and the brakes are not released until pressure is restored in pipe 50. When diaphragm 341 yields to the force due to rotation of the centrifuge and thus allows shaft 20 to move to the right, the balls

of the governor fly out to a further distance from the center of rotation and increase thereby the centrifugal force at the given speed. Consequently, if the force exerted by the spring and air pressure remains constant, the speed of the governor must decrease to a value less than the speed which caused the application of the brakes, before the force exerted by diaphragm 341 again overcomes the force due to the action of the centrifuge.

Since governor 4 always rotates at a speed proportional to the speed of the vehicle, the speed of the vehicle is limited by the force which counteracts the force exerted on the diaphragm due to the rotation of the centrifuge. As a concrete example suppose that the apparatus is so proportioned that, when the vehicle travels at the rate of 50 miles per hour, and when air at a pressure of 70 lbs. per square inch is admitted through port 39 to cylinder 34, the forces on the opposite sides of the diaphragm balance each other. Any increase in speed of the vehicle will augment the force due to the centrifuge, whereby the diaphragm is displaced, valve 44 is opened and the brakes are applied. Due to the increase of moment of the governor balls, the brakes remain applied until the speed of the vehicle has been lowered to say 35 miles per hour. Then shaft 20 moves back to the left, valve 44 is closed, pressure builds up in pipe 50 and the brake application valve acts to release the brakes. If air pressure is admitted to cylinder 34 through port 40, and at the same time the air pressure is allowed to exhaust from the middle compartment of cylinder 34, the force acting against diaphragm 341 will be less, so that the speed of the vehicle will be limited to a lower value, say 20 miles per hour. When the air remaining in the cylinder 34 back of piston 36 is exhausted through port 40 the speed of the vehicle will be limited to a still lower value, say 10 miles per hour. It will be noted that my device is constructed so as to embody the fundamental principles of safety. The application of the brakes is caused by centrifugal force—a force as reliable and absolute as gravity. Failure of air pressure in cylinder 34 causes either a medium speed limit or a low speed limit. Failure of spring 37 causes the vehicle to come to a stand-still.

For the control of air pressure in cylinder 34 any convenient apparatus may be used. In Fig. 2 I have shown one form of such control apparatus, which is operatively connected by pipes 120 and 121 with the apparatus described above.

In Fig. 2 I have shown four cylinders, 51, 52, 53 and 54, the axes of which are co-linear. Cylinder 52 is of larger diameter than cylinder 51; and cylinders 53 and 54, both of the same diameter, are larger in

diameter than cylinder 52. Air may freely pass from cylinder 51 into cylinder 52, and cylinders 52 and 53 communicate with each other by a port 55. Cylinders 53 and 54 are separated by cylinder head 54^a. A piston 110 in cylinder 52 is provided with a small orifice 128, so that the air pressure normally equalizes on both sides of the piston. But, when piston 110 is in the extreme right end 10 of its stroke, an annular projection 139 on piston 110 seals against a gasket 140 preventing the escape of air through port 128 to cylinder 53. A slide valve 56, operatively connected to piston 110, is movable in suitable guides in cylinder 51. This slide valve 15 controls ports 57, 58, 59, 60 and 125 of cylinder 51 as will be explained hereinafter. Air is admitted to cylinder 51 through a port 63 and a pipe 621 from a source of 20 approximately constant pressure shown as main reservoir 61. Cylinder 53 contains a piston 62 movable through a distance marked "c." In the position in which the piston is shown in Fig. 2 leakage of air 25 from cylinder 53 past piston 62 is prevented by a gasket 64. When piston 62 is moved to the left through the distance "c," piston rod 66 pushes piston 110 and slide valve 56 through the same distance. But, when the 30 piston is moved from left to right due to a decrease in the air pressure on the right hand face of piston 62 the slide valve 56 and piston 110 do not follow, since piston rod 66 is not connected to piston 110. Cylinder 54 which is shorter than cylinder 53 contains a piston 631 which can move through a shorter distance indicated by "b" 35 on the drawing. Piston rod 67 is not connected with piston 62, so that although piston 40 ton 631 can move piston 62 to the left through a distance "b," it cannot move piston 62 to the right. Upon cylinder 51 are mounted two double pin valves 68 and 69, the lower valves 70 and 71 of which are held 45 normally closed by means of springs 82 and 83 respectively, and the upper valves 72 and 73 of which are held normally open by the same means. Valve stems 74 and 75 are attached to rods 76 and 77, the upper ends 50 of which are attached to armatures 78 and 79 of electromagnets 80 and 81. When these electromagnets are energized they attract their armatures, thus opening the lower valves 70 and 71 and closing the upper valves 55 72 and 73. Double pin valve 68, when actuated by magnet 80 allows air to pass from cylinder 51 through a port 84, valve 70, a passage 86, a ball check valve 88, a pipe 90 and a port 92 into cylinder 54. Double pin 60 valve 69, when actuated by magnet 81 admits air from cylinder 51 through a port 85, a valve 71, a passage 87, a ball check valve 89, a pipe 91 and a port 93 into cylinder 53.

65 The energizing circuits of magnets 80 and

81 are controlled by contact shoes 94 and 95 respectively. These contact shoes are rigidly attached to and electrically insulated from plungers 96 and 97, capable of reciprocation in the guides 98 and 99 respectively. 70 Springs 100 and 101 are provided to bias the plungers to the lower extreme position. Plunger 97 is provided with a projecting trip 102, which is adapted to strike the valve stem 104 of a valve 103, after plunger 97 75 has completed part of its upward stroke. Valve 103 is normally held closed by a spring 105. When open, it permits air to flow from a pipe 107 through a port 106 to atmosphere. 80

Contact shoes 94 and 95 are adapted to engage ramp rails 108 and 109 respectively, located in the trackway. Contact shoe 94 and ramp rail 108 are not in the same vertical plane as contact shoe 95 and ramp rail 85 109. For example, the former may be located in a vertical plane midway between the track rails, and the latter in a vertical plane outside the track rail. Ramp rails 108 and 109 may be energized by batteries K and K', through circuit controllers P and P', as will be explained in the description 90 of Figs. 3 and 4.

When the parts of the apparatus on the car are in the positions shown in Figs. 1 95 and 2, which I will term the "slow-speed" position, cylinders 51 and 52 are under pressure of air from reservoir 61. The slide valve 56 is held at the right end of its stroke by air pressure in cylinder 51 acting on piston 110, the opposite side of piston 110 being connected to atmosphere through port 55, pipe 126, port 58 of cylinder 51, cavity 119 of slide valve 56, and port 57 of cylinder 51. In this position, the chamber between pistons 35 and 36 of cylinder 34 is open to atmosphere through port 39, pipe 122, pipe 121, port 59, cavity 119 and port 57. The chamber between piston 36 and cylinder head 38 is also open to atmosphere 100 105 through port 40, pipe 120, port 60, to cavity 119 and port 57. Consequently spring 37 is the only force that resists the force on the diaphragm 341 due to the action of the centrifuge, and the vehicle is limited as previously explained to a speed of, say, 10 110 miles per hour. A reservoir 124, used for a purpose to be pointed out later, is connected to pipe 121 by means of a pipe 123 and is therefore also under atmospheric 115 120 pressure.

To change from low speed to medium speed, contact P is closed to energize ramp 108, and contact P' is opened to deenergize ramp 109. If contact shoe 94 now 125 makes contact with the energized ramp 108 the following circuit is closed: from battery K, through circuit controller P, ramp 108, contact shoe 94, wire 117, energizing winding 80^a of electromagnet 80, wire 118, slid-

130

ing contact 119^a on car wheel 2, wheel 2, and track rail 1 back to battery K. Thus electromagnet 80 is energized and operates double pin valve 68, so that air is admitted 5 to the right hand side of piston 631 from port 84 of cylinder 51, valve 70, passage 86, past ball check valve 88, pipe 90 and port 92. The left hand side of piston 631 and the right hand side of piston 62 are connected to atmosphere through pipe 91, small 10 passage 130, passage 87, and valve 73. While contact shoe 95 is on the upper portion of ramp 109, trip 102 engages with valve stem 104 to open valve 103, thereby connecting 15 the left hand side of piston 62 to atmosphere through port 55, pipe 107 and exhaust port 106 of valve 103. Since the area of piston 631 is greater than that of piston 110 the force acting on piston 631 is greater than 20 that acting in opposition on piston 110, and as a result, pistons 631, 62 and 110 and slide valve 56 are displaced to the left through the distance "b". The new position of the slide valve 56 with respect to the ports of 25 cylinder 51 I have shown in Fig. 2^b. Port 60 is now uncovered and air pressure is admitted to cylinder 34 through port 60, pipe 120 and port 40 of cylinder 34, forcing piston 36 against stop 41. Thus spring 37 is 30 compressed, and as explained above, the vehicle may travel at a speed higher than before, say, 20 miles per hour. As soon as contact shoe 95 leaves the higher portion 35 of ramp 109, valve 103 closes and air pressure passing through the orifice 128 from cylinder 51 builds up pressure on the right hand side of piston 110 and in cylinder 53, pipes 107 and 126, pipe 126 now being closed at port 58 by valve 56. The forces tending 40 to move valve 56 are now balanced, hence valve 56 remains in the position shown in Fig. 2^b, which I will call the "medium speed" position. When contact shoe 94 leaves ramp 108, valve 70 is again closed 45 and valve 72 is opened, connecting the right hand side of piston 631 to atmosphere through port 92, pipe 90, small passage 129, passage 86 and valve 72. The purpose of the ball check valve 88 and the small passage 50 129 is to retard the rate of reduction of pressure to insure that the pressures on both sides of piston 110 will have equalized before the pressure of piston 631 against pistons 62 and 110 is removed. After a 55 short interval of time, therefore, the air pressure in chamber 53 will force pistons 62 and 631 back into the positions shown in Fig. 2, whereas piston 110 remains in the medium speed position. If, due to the vibration of the vehicle, valve 56 were gradually caused to travel to the left, a dangerous condition would arise, for the valve would ultimately reach the high speed position to be described below. To prevent this, I provide valve 56 with a cavity 134. Then, as

valve 56 travels toward the left, port 58 and pipe 126 are connected to atmosphere by cavity 134 and port 57 and in consequence, the pressure is diminished on the right side of piston 110, causing the latter to move 70 back to the medium speed position. Thus port 58 is again closed and pressure on the two sides of piston 110 equalized.

If now ramp 109 (which I will term the "high speed" ramp) is energized when it is 75 engaged by shoe 95, current flows in the following circuit: from battery K', through circuit controller P', ramp 109, contact shoe 95, wire 131, energizing winding 81^a of magnet 81, wire 118, contact 119^a, wheel 2, rail 80 1 to battery K'. Thus magnet 81 is energized and actuates double pin valve 69 to admit air to the right hand side of piston 62 from port 85 of cylinder 51, valve 71, passage 87, past ball check valve 89, pipe 85 91 and port 93. While contact shoe 95 is on the upper portion of ramp 109, trip 102 engages valve stem 104 opening valve 103 and allowing air to exhaust from the chamber to the left of piston 62. Consequently 90 piston 62 is moved to the left through distance "c" forcing slide valve 56 to its extreme left hand position, which I will term the "high speed" position, this being the position in which the valve is shown in Fig. 95 2^c. Port 59 is now uncovered so that air enters cylinder 34 between pistons 35 and 36, forcing piston 36 back against cylinder head 38, as explained above. Air pressure is now exerted directly against the full area of the 100 diaphragm and the speed of the vehicle may be increased to its highest allowable value, which I assumed to be 50 miles per hour. Reservoir 124 also is filled with air pressure. 105 As soon as contact shoe 95 leaves the higher portion of ramp 109, valve 103 closes, and air pressure passing through the orifice 128 from cylinder 51 builds up pressure on the right hand side of piston 110 and on the left hand side of piston 62 and in pipe 107 and 126 as before. Hence, slide valve 56 remains 110 in the position shown in Fig. 2^c. When contact shoe 95 leaves ramp 109, magnet 81 is deenergized and double pin valve 69 is returned to its normal position. Air gradually exhausts from the right hand side of piston 62 through port 93, pipe 91, small passage 130, passage 87 and valve 73. After a short interval of time, therefore, the air pressure in chamber 53 will force piston 62 120 back into the position shown in Fig. 2, piston 110 remaining in its extreme left or "high speed" position.

Suppose now that while slide valve 56 is 125 in the high speed position, the vehicle reaches a location in the track where there are two ramp rails 108 and 109 placed parallel to each other, only the medium speed ramp 108 being energized and the high speed ramp 109 deenergized. Then as con- 130

tact shoes 94 and 95 make contact with their respective ramps only magnet 80 is energized. Trip 102 then opens valve 103 and as previously explained, air pressure is exhausted from the left hand side of piston 62, pistons 631 and 62 are moved to the left through distance "b," and piston 110 is moved to the right from its position at the extreme left until it comes into contact with piston rod 66. Thus slide valve 56 is moved to the "medium speed" position, and it remains there, whereas piston 62 and 631 are returned to the extreme right position, as previously explained. By moving to the "medium speed" position, slide valve 56 connects port 59 to atmosphere by means of cavity 119 and port 125 which latter is an orifice of restricted area. The air in reservoir 124 and in cylinder 34 between pistons 35 and 36 then discharges through orifice 125, at a predetermined rate, depending upon the relative proportions of orifice and reservoir. As a result the pressure against diaphragm 341 is gradually reduced, and the speed limit imposed upon the vehicle by the control apparatus diminishes at a predetermined rate from the "high speed" limit to the "medium speed" limit. Thus, if in the above example the engineman reduces the speed of the vehicle from 50 miles per hour to 20 miles per hour at a rate of change equal to or greater than that determined by the reservoir 124 and orifice 125, an automatic application of the brakes by the control apparatus will be avoided.

If the speed of the vehicle is not reduced, the brakes are applied automatically. They are applied at once if the vehicle is traveling at its highest speed, and are applied after an interval of time when the speed of the vehicle is less than the maximum, the length of this time being greater when the speed of the vehicle is low.

If, while the slide valve 56 is in the "high speed" position or the "medium speed" position, the vehicle passes two ramps 108 and 109 both of which are deenergized, or one ramp 109 which is deenergized, neither magnet 80 nor 81 is energized, but valve 103 is opened. Consequently air exhausts from cylinder 53 to atmosphere and the valve 56 is moved to the low speed position by air pressure acting on the left side of piston 110. After piston 110 has reached the low speed position, the annular rib 139 on piston 110 presses against gasket 140 and so prevents the escape of air from cylinder 52 through ports 128 and 55 to atmosphere. Slide valve 56 is thus returned to its low speed position and pipe 120 is opened to atmosphere, thus removing all pressure from diaphragm 341 except that exerted by the spring 37, so that the low speed (10 miles per hour in the case assumed) is imposed by the speed controlling apparatus.

Referring now to Fig. 3, I have here shown a railroad track, having track rails 1 and 1' divided into sections, A, B, C, etc., by means of insulated joints 111. This track is equipped with a signaling system, preferably one which is capable of giving three indications, viz., "proceed", "caution" and "stop". I have shown on the drawing a signaling system using semaphore signals S^B, S^C, etc., of the three position type, although I do not wish to limit myself to any particular type of signal. The circuits by which these signals are controlled form no part of my invention, hence I have omitted them to avoid unnecessary confusion. Ramps 109^a and 109^b are located along the track, one of the former being placed at approximately maximum braking distance in the rear of the entrance to each block, and one of the latter being located adjacent the entrance end of each block. As here shown, ramps 109^a and 109^b are located at equal distances from the track rails, so that the contact shoe 95 of a train V equipped as shown in Figs. 1 and 2 makes contact with them successively as the train moves along the track.

Circuit controllers P^B, P^C, P^D, etc., provided for a purpose to be pointed out below, are operatively connected with the semaphore arms 112 of signals S^B, S^C, S^D, etc., respectively. Each circuit controller has, as here shown, a contact finger 138 operatively connected with the semaphore, a fixed contact point 135 and a fixed contact strip 137. Batteries K^B, K^C, etc., are provided one for each block. One terminal of each battery is connected to the track rail 1 of the preceding block section by means of wire 115, the other terminal being connected to the ramps 109^a and 109^b by wire 114, switch P, and wires 113 and 116, whenever contact finger 138 of switch P is in such a position that it will make contact with strip 137.

Suppose that block section D is occupied by a train V'. Then in the system of signaling which I have used for illustration, signals S^D, S^C and S^B will indicate "stop", "caution" and "proceed" respectively. Accordingly a second train V equipped with apparatus as shown in Figs. 1 and 2 approaching block B in the direction of the arrow, should be allowed to enter that block at full speed. Ramp 109^b at the entrance to block B is energized, switch P^B being closed because signal S^B indicates "proceed". Consequently current flows from ramp 109^b through the circuit on the train as described for Fig. 2 to the track rail 1, and by the operation of apparatus described above, the train is permitted to travel at the highest speed, which I assumed to be 50 miles per hour.

Since at block C the signal indicates cau-

tion and switch P^c is closed, the ramps 109^a and 109^b adjacent the entrance of this block are energized and the speed of the train may continue to be 50 miles per hour.

5 The signal S^p , however, stands at stop and switch P^p is open. Consequently ramp 109^a, braking distance in the rear of the entrance to block D, is deenergized. As a result the control apparatus on the train imposes a speed limit which gradually reduces 10 from a maximum of 50 miles per hour to 10 miles per hour, and unless the speed of the train is reduced, the brakes are automatically applied so that under no condition 15 can the speed of the train exceed 10 miles per hour at ramp 109^b at the entrance to block D. Thus train V is prevented from passing stop signal S^p at a speed in excess of 10 miles per hour.

20 Suppose now that train V' has moved out of block D and into block E by the time that train V reaches ramp 109^b at the entrance to block D. Then signal S^p does not indicate "stop", but "caution". Ramp 109^a 25 is energized and accordingly the train V' may resume full speed and it may continue at this speed until it meets the next rail 109^a, when it must again reduce speed unless train V' has left block E.

30 The apparatus shown in Figs. 1 and 2 is particularly adapted for use in connection with a railway on which, owing to curves and grades, it is desirable to enforce at times a medium speed limit, such, for example, as 20 miles per hour. Such a condition 35 is illustrated in Fig. 4, in which I have shown a railroad track divided into block sections G, H, etc., two of the block sections I and J being on a down grade.

40 The block sections are all equipped with apparatus such as shown in Fig. 3. In addition I provide ramps 108^a and 108^b for the block sections, I, J and K, situated parallel to ramps 109^a and 109^b, so that contact shoe 45 94 of train V can make contact with them as shown diagrammatically in Fig. 2. In these blocks the wires 113 and 116 which in Fig. 3 connected ramp 109^a and 109^b to battery K are connected to the ramps 108^a and 50 108^b, so that these ramps are energized when the switch P is closed, but the corresponding ramps 109^a and 109^b are never energized.

55 Suppose train V' occupies block K. Then, with the control apparatus used in Fig. 3, a train V may be running at the speed of 50 miles an hour when it reaches ramp 109^a in the rear of the entrance to block K. But, on a down grade, the speed of the train V cannot be reduced from 50 to 10 miles per 60 hour within this distance, even were ramp 109^a located a full block in the rear of the entrance to block K.

65 The modification of my system shown in Fig. 4 overcomes the above difficulty. At the entrance to block H the ramp 109^b is en-

ergized and the vehicle may proceed at high speed into block H in the direction of the arrow. The next block I should not be entered at this high speed, even though signal S^i indicates "proceed", because block I is on a down grade. When the vehicle proceeds in block H and encounters ramps 108^a and 109^a, of which only ramp rail 108^a is energized, the control mechanism is operated as explained in the description of Fig. 2 and the speed limit of the train is gradually reduced to the medium speed limit, say 20 miles per hour. Unless the speed is gradually reduced as the train approaches block I, the brakes are applied automatically, so that at the entrance to block I the speed of the train is 20 miles per hour or less.

The signal S^j at the entrance to block J indicates caution, consequently the ramps 108^a and 108^b controlled by signal S^j are energized and the train may enter block J at medium speed.

Signal S^k at the entrance to block K indicates stop. Therefore the ramps controlled by signal S^k are not energized, and, unless the speed of the train has already been reduced, the brakes are applied automatically so that the train is prevented from passing stop signal S^k at a speed in excess of 10 miles per hour.

If then train V' proceeds out of block K, and has also passed out of block L by the time train V reaches ramp 109^a controlled by signal S^l , this ramp is energized and the train V may speed up again to its maximum speed of 50 miles per hour.

Thus my apparatus enforces a continuous speed limit, the limit over any section of track being the maximum safe speed under the particular condition of track and block.

In Fig. 5 I have shown a modification of the electropneumatic control apparatus of Fig. 2. In this modification I employ but a single contact shoe 95 and corresponding magnet 81 and pin valve 69. Cylinder 54 which in Fig. 2 is connected to the second pin valve is in this modification connected to pipe 121 by means of a pipe 300 and port 301. By this means piston 631 is held in the extreme left position, in other words, the valve 56 is held or moved to the medium speed position when the pressure on the right hand side of piston 631 is greater than the pressure on the left hand side of piston 62. I assume furthermore that the tension of spring 37 of Fig. 1 is such that it exerts no force against diaphragm 341 unless piston 36 is forced to the left due to air pressure in pipe 120, so that when the air pressure is exhausted from both pipes 120 and 121 the brakes will be applied automatically if the train is run at any speed. When spring 37 is compressed due to the displacement of piston 36 because of air pressure 125 130

from pipe 120, the speed limit is raised, for example to 10 miles per hour, which I shall call the low speed limit. The high speed limit is controlled in the same manner as in 5 the apparatus shown in Fig. 2.

To explain the operation of the apparatus shown in Fig. 5, suppose all the parts are in the positions shown in the drawing. Slide valve 56 is in the high speed position, 10 so that reservoir 61 supplies air pressure to cylinder 51, and all the passages open there- 70 to, *i. e.*, to pipes 121 and 120 through ports 60 and 59 and to cylinder 53 and pipes 107 and 126 through orifice 128 in piston 110. 15 Furthermore, pistons 62 and 631 are dis- 75 placed to the left through distance "b" because air pressure has entered cylinder 54 through port 301. The train may therefore proceed under the maximum speed limit.

20 Suppose now that the train encounters a deenergized ramp 109. Then valve 103 is opened by trip 102 carried by contact shoe 95, and air pressure exhausts through pas- 80 sages 55 and 107 and exhaust port 106 of 25 valve 103 to atmosphere. Thus the pressure 85 on the right side of piston 110 is lowered and piston 110 and valve 56 are moved to the right into engagement with piston rod 66 of piston 62, *i. e.* into the position indicated 30 in Fig. 2^B. Thereby port 59 is opened to cavity 119 of slide valve 56 which communi- 90 cates with atmosphere through orifice 125. Consequently the air pressure in reservoir 124 and cylinder 34 is gradually reduced 35 causing a gradual decrease in the speed 95 limit from the highest value, which I assume as 50 miles per hour, to the lowest of 10 miles per hour. Since the connection to atmosphere through pipe 107 and valve 103 40 is closed as soon as the train has passed beyond ramp 109, air flows from cylinder 51 through orifice 128 of piston 110 into cylinder 52 and through passage 55 into cylinder 53, thereby developing full pressure on 45 the left hand side of piston 62. But since 100 the right hand side of piston 631 is connected to pipe 121, in which the air pressure is decreasing, pistons 62 and 631 are forced to the right. Valve 56 remains in 50 the position shown in Fig. 2^B, because the 105 pressures on the two sides of piston 110 are equalized.

Suppose now that the train encounters a 55 second deenergized ramp 109. Then valve 103 is again opened, and air pressure is ex- 110 hausted from pipe 107 causing piston 110 to be forced to the right into the position shown in Fig. 2^A due to the air pressure in cylinder 51. Now valve 56 connects ports 60 59 and 60 to atmosphere through cavity 119 and port 57. Piston 36 of cylinder 34 is forced to the right by the expansion of spring 37 and since the diaphragm is now unsupported by any force on its right, the 65 vehicle is brought to an absolute stop.

If ramp 109 is energized, magnet 81 operates double pin valve 69 so as to allow air pressure from cylinder 51 to enter cylinder 53 through pipe 91 and port 93. As a result, piston 62 is forced to its left extreme 70 position and moves slide valve 56 to the position indicated in Fig. 2^C. Air pressure now enters pipes 121 and 120 restoring all the apparatus to the original position shown in Fig. 5 and the speed of the vehicle may again be brought up to the maximum value. 75

In Fig. 6 I have shown a modification of the control system for the apparatus shown in Fig. 1. The form shown in this modification is in a sense an electromechanical 80 equivalent of the piston slide valve apparatus shown in Fig. 2. The apparatus shown in Fig. 6 is also so arranged that it is adapted for the control of trains consisting of a number of similar cars, each of which 85 is equipped with the apparatus shown in Figs. 1 and 6. Four wires 150, 151, 152, 153 are provided for each car, each wire being connected to the corresponding wires of the adjacent cars by means of couplers 154. A 90 battery 155 is permanently connected to wires 150 and 151 by means of wires 156 and 157. Contact shoes 162^a and 162^b are located at diagonally opposite corners of the vehicle so that one of the contact 95 shoes 162^a and 162^b is always in position to engage a ramp 109 a number of which are disposed at intervals on either side of the running rails, as will be described hereinafter. A third contact shoe 163 is located 100 on the center line of the car, so that it engages a ramp 108, a number of which are placed at intervals midway between the running rails. Operatively connected to contact shoes 162^a and 162^b are circuit 105 controllers 164^a and 164^b respectively, each having contact bars 165 and 166, electrically insulated from control rod 167, and adapted to bridge contact points 168—169 and 170—171 respectively. These circuit controllers are 110 biased normally to closed position by means of springs 172, and opened by means of trips 173 adapted to engage rods 167 during the upper portion of their stroke. Each car is provided with two relays 158 and 159 re- 115 sponsive to alternating current and with two relays 160 and 161 responsive to direct current. The energizing circuits of relays 158 and 159 are partly on the car and are partly on the roadside. Thus relay 158 is connected 120 to contact shoes 162^a and 162^b by wires 218 and 188 respectively, and to a sliding contact 119^a on a car wheel by means of wire 211. Similarly, relay 159 is connected to contact shoe 163 by means of wire 210 and 125 to sliding contact 119^a by wire 211.

The roadside part of the energizing circuits of relays 158 and 159 will be described in detail hereinafter. Suffice it now to point out that ramp 108 or 109 may be energized 130

by connecting one terminal of the secondary of a transformer T or T' to a running rail 1 and connecting the other terminal of the secondary of transformer T or T' through 5 a circuit controller P or P' to ramp 108 or 109. Hence relays 158 or 159 are energized as long as either contact shoes 162^a or 162^b, or 163 make contact with an energized ramp 109 or 108 respectively. Relay 160 may be 10 energized by current flowing in the following circuit: from battery 155, through wires 156, 150 and 197, contact 189 of relay 158, wire 191, relay 160, wires 192, 151 and 157 to battery 155. Therefore, in order that relay 15 160 may be energized, relay 158 must first be energized by current from ramp 109 as described above. Once relay 160 is energized, however, it will remain energized by current flowing in its stick circuit, which 20 circuit is as follows: from battery 155 through wires 156, 150 and 505, contact bar 166 of circuit controller 164^a, wire 206, contact bar 166 of circuit controller 164^b, wire 209, contact 193 of relay 160, relay 160, 25 wires 192, 151 and 157 to battery 155. Thus relay 160 remains energized until its stick circuit is broken by opening either circuit controller 164^a or 164^b. Similarly, relay 161 is energized by current flowing in the circuit: from battery 155 through wires 156, 30 150 and 197, contact 212 of relay 159, wire 213, relay 161, wires 192, 151 and 157 to battery 155. When relay 161 is energized it is held so by current flowing in its stick circuit: 35 from battery 155, wires 156, 150 and 505, contact bar 165 of circuit controller 164^a, wire 214, contact bar 165 of circuit controller 164^b, wire 208, contact 202 of relay 161, relay 161, wires 192, 151 and 157 to 40 battery 155. Thus relay 161 remains energized until its stick circuit is opened at either circuit controller 164^a or 164^b.

The cab of each car is provided with three signal lights R, Y, G, colored preferably 45 red, yellow and green, respectively. Red lamp R is energized through the circuit: from battery 155, wires 156, 150, 197 and 198, back contact 205 of relay 161, wire 199, back contact 196 of relay 160, wire 200, red lamp 50 R, wires 192, 151 and 157 to battery 155. Thus red lamp R is displayed when both relays 160 and 161 are deenergized. Green lamp G is energized by current flowing through the following circuit: from battery 55 155, wires 156, 150, 197 and 198, back contact 205 of relay 161, wire 199, front contact 195 of relay 160, wire 202, green lamp G, wires 192, 151 and 157 to battery 155. Hence, a green light is displayed when relay 60 160 is energized and relay 161 is deenergized. The circuit for yellow lamp Y is as follows: from battery 155, through wires 156, 150, 197 and 198, front contact 204 of relay 161, wire 215, yellow lamp Y, wires 65 192, 151 and 157 to battery 155. Therefore,

a yellow light is displayed when relay 161 is energized. From the above arrangement of circuits it is seen that only one light can be displayed at a time.

Magnets 80 and 81 operate double pin 70 valves 68 and 69 in the manner described in connection with Fig. 2. The energizing circuit of magnet 81 is as follows: from battery 155, wires 156, 150, 197 and 198, back contact 205 of relay 161, wire 199, front contact 75 195 of relay 160, wire 202, energizing winding 81^a of magnet 81, wires 225, 192, 151 and 157 to battery 55. Therefore, magnet 81 is energized only when relay 161 is deenergized and relay 160 is energized. The 80 energizing circuit of magnet 80 is as follows: from battery 155, wires 156, 150, 197 and 198, front contact 204 of relay 161, wire 215, winding 80^a of magnet 80, wires 192, 151 and 157 to battery 155. Hence, magnet 85 80 is energized when relay 161 is energized. It is evident from the above that magnets 80 and 81 cannot be energized simultaneously. When magnet 80 is deenergized, spring 82 holds valve 72 open thus connecting 90 pipe 120, which leads to port 40 of cylinder 34 in Fig. 1, to atmosphere. When magnet 80 is energized, upper valve 72 is closed and lower valve 70 is opened, thus admitting air pressure from main reservoir 95 61 through pipe 181, port 84, valve 70 to pipe 120 leading to the right hand side of piston 36 of Fig. 1. Similarly when magnet 81 is deenergized, pipe 121, which is connected to pipes 122 and 123 in Fig. 1, is 100 opened to atmosphere, and when magnet 81 is energized, pipe 121 is connected to main reservoir 61.

In addition to the cab signal lights I provide a pressure gage 185, which is connected 105 to pipe 121 to indicate the pressure therein. Since the pressure in pipe 121 has a definite relation to the speed limit imposed upon the vehicle by the control magnet 81, the pressure gage may be calibrated empirically in 110 terms of the permissive speed of the vehicle. Not being connected to pipe 120, this pressure gage does not indicate the variation of speed limit imposed upon the vehicle due to the control effected by the action of magnet 80. 115

To explain the operation of this form of my train control apparatus, assume that a train of one or more cars, each of which is equipped with the apparatus shown in Figs. 1 and 6, travels along the track rails one of which is shown on Fig. 6 and is designated by reference character 1. Assume furthermore that all parts of the apparatus are in the positions shown in Fig. 6. Then all relays are deenergized, consequently magnets 80 and 81 are deenergized, their circuits being broken at contacts 204 and 195 of relays 161 and 160 respectively. Hence, atmospheric pressure exists in pipes 120 and 121. 120 125 130

For that reason the only force opposing the force exerted on diaphragm 341 due to the action of the centrifugal governor 4 is that exerted by spring 37. As a result the low speed limit of 10 miles per hour is imposed on the car or train as explained hereinbefore. The pressure gage 185 indicates therefore atmospheric pressure in pipe 121, which may be marked 10 miles per hour on the scale. Red lamp R is illuminated, its circuit being completed through the back contacts 205 and 196 of relays 161 and 160.

Assume now that the train encounters an energized ramp 109. As either contact shoe 162^b or 162^a of the first car of the train engages the ramp, alternating current flows in the energizing circuit of relay 158, which circuit is from secondary of transformer T' through contact P', wire 187, contact 109-20 162^a, or 109-162^b, wire 218 or 188, relay 158, wire 211, axle 119, wheel 2, rail 1, wire 186, to secondary of transformer T'. The contacts of relay 158 are therefore closed. Contact 189 of relay 158 closes the energizing 25 circuit of relay 160, which therefore becomes energized and closes its front contacts. As a result magnet 81 is energized, its circuit being closed at front contact 195 of relay 160 and back contact 205 of relay 161, and 30 in attracting its armature it opens lower valve 71 and closes upper valve 73 of double pin valve 69. Air pressure enters pipe 121 from reservoir 61 and flows into reservoir 124 and cylinder 34 of Fig. 1, and thereby 35 cutting in the "high speed" limit on the first car. The rise in pressure in pipe 121 is indicated by pressure gage 185. The circuit for green lamp G is closed through front contact 195 of relay 160 and back contact 40 205 of relay 161, so that a green light is displayed in the cab, the circuit for red lamp R being broken at contact 196 of relay 160.

Since as previously stated each car of 45 the train is to be equipped with the speed control apparatus, it is obviously necessary to apply the "high speed" control on all cars of the train in order to permit the train to resume full speed. It is also desirable, 50 in order to permit the train to get under way without delay, and in order that the cab signal and speed limit indicator on the first car will correctly indicate conditions on the entire train, that the "high speed" 55 control on the following cars be applied simultaneously with that on the first car, or in other words, that the relays 160 on each car of the train be energized at the same time the relay 160 of the first car is energized, due to the energization of relay 158 of 60 the first car from an energized ramp 109. This is accomplished as follows:

When front contact 190 of relay 158 closes, battery 155 is connected to train wire 65 152 through the connection; from battery

155, wires 156, 150 and 197, contact 190 of relay 158 and wire 225 to wire 152, which by couplers 154 is made continuous through the length of the train. Then relay 160 on each car of the train becomes energized 70 through the following circuit: from wire 152, through wire 225, back contact 194 of relay 160, energizing winding of relay 160, wires 192, 151 and 157 to battery 155. The contact finger 221 of each relay 160 is of 75 such construction that front contact 193 closes before back contact 194 opens. As soon as front contact 193 is closed, relay 160 is held energized through the stick circuit traced hereinbefore. With relay 160 of 80 every car energized, magnet 81 of each car is energized, hence, the high speed limit of 50 miles per hour is applied to the whole train.

Since the speed control equipment on each 85 car of the train is identical, it is evident that if the ramp 109 is deenergized when passed by the first car and is energized at any time before it is passed by the last car of the train, the car whose contact shoe is 90 in engagement with the ramp at the time it becomes energized will serve the function of the "first car" described in the preceding paragraph, to simultaneously apply the "high speed" control on all cars of the train to 95 permit an immediate acceleration to full speed. This is of great advantage in increasing the traffic capacity, as it permits a train which has been held down to a low speed due to unfavorable conditions ahead, 100 to immediately resume full speed upon the closing of circuit controller P' due to the removal of the unfavorable condition provided some car of the train is in engagement with a ramp, and in fact permits continuous control of the train by circuits located in the roadway, without the employment of a continuous roadside contact rail, provided that the successive ramps are 105 spaced a distance apart not greater than the 110 length of the trains.

For another illustration of the operation of the above form of my system of train control, assume that the first car of the train next encounters a ramp 109 which has been 115 deenergized by opening the corresponding switch P. Then relay 158 is, of course, not energized, but the stick circuit of relay 160 is broken by circuit controller 164^a or 164^b. As a result relay 160 opens its front contacts, thereby breaking the energizing circuit of magnet 81 at contact 195. Consequently spring 83 closes lower valve 71 and opens upper valve 73 of double pin valve 69. Pipe 121 is therefore open to atmosphere and the air pressure in cylinder 34 and reservoir 124 is exhausted through valve port 73, which port is restricted in area so that the reduction of pressure in reservoir 124 and cylinder 34 is gradual. Thus the 120 125 130

force exerted against diaphragm 341 is gradually diminished and the speed limit is gradually decreased from 50 miles per hour to 10 miles per hour. This is indicated by 5 gage 185. Green lamp G, the circuit of which is broken at front contact 195 of relay 160, is extinguished, and the red lamp R is displayed, because its circuit is closed by back contact 196 of relay 160.

10 In the case of a train of more than one car, this process is repeated for every car of the train as it passes the ramp 109.

Assume that the first car of the train next encounters an energized ramp 108. Contact shoe 163 engages this ramp causing alternating current to flow in the energizing circuit of relay 159, which circuit is from secondary of transformer T, through contact P, wire 211, contact 108-163, wire 210, 15 relay 159, wire 211, thence through the axle, wheel and rail, to transformer T. The front contacts of relay 159 are therefore closed. The energizing circuit of relay 161 is closed at contact 212 of relay 159, hence 20 relay 161 closes its front contacts. Contacts 204 of relay 161 closes the energizing circuit of magnet 80 which therefore attracts its armature thereby opening lower valve 70 and closing upper valve 72 of double pin 25 valve 68. Thus air pressure is admitted to pipe 120 from reservoir 61 and by exerting pressure against piston 36 in cylinder 34 of Fig. 1 it compresses spring 37. Now piston 35 of cylinder 34 presses against diaphragm 341 with a pressure corresponding to the 30 medium speed limit. The circuit for red lamp R is broken at back contact 205 of relay 161 and the circuit for yellow lamp Y is closed at front contact 204 of relay 35 40. Consequently, the red light is extinguished and the yellow light is displayed.

Relay 159 also closed contact 222 to energize train wire 153 by the following circuit: from battery 155, wires 156, 150 and 197, 45 contact 222 of relay 159, wire 223 to wire 153. By means of couplers 154, wire 153 of every car of the train is energized. Hence on each car of the train, the circuit is completed from wire 153 to wire 223, back contact 203 of relays 161, energizing winding of relay 161, wires 192, 151 and 157 to battery 155. Contact finger 232 of relay 161 is constructed so as to close the front contact 202 before it opens back contact 203. 50 55 As a result each relay 161 remains energized through its stick circuit once it has been energized. Thus magnets 80 of each car of the train are energized simultaneously. Similarly, magnets 80 of each car of the train will be energized simultaneously if ramp 108 is deenergized when passed by the first car of the train, but is energized by closing circuit controller P before it is passed by the last car of the train.

If now the first car of the train simultaneously encounters ramps 108 and 109 both of which are deenergized, or encounters a deenergized ramp 109 alone, neither relay 158 nor 159 is energized but the stick circuit of relay 161 is broken by circuit controller 164^a or 164^b and, as a result, relay 161 is deenergized. Consequently, magnet 80 is deenergized, its circuit being broken at contact 204 of relay 161. Air pressure in pipe 120 and behind piston 36 of cylinder 34 is exhausted through upper valve 72 of double pin valve 68, allowing spring 37 to expand. As a result the low speed limit is imposed on the car. The circuit for the yellow lamp Y is broken at contact 204 and the circuit for red lamp R is closed at contact 205 of relay 161. Hence the yellow light is extinguished and the red light is displayed. This process is repeated by the apparatus on each car of the train as the contact shoes of each car encounter the deenergized ramps and as a result the lowest speed limit is applied to each car of the train in succession.

Assume that as the train proceeds under the "high speed" limit, the first car of the train encounters ramps 108 and 109 of which ramp 108 is energized and ramp 109 is deenergized. Relay 159 is then energized by current flowing from ramp 108 and closes the circuit of relay 161 at contact 212. Relay 161 opens at back contact 205 the circuit of red lamp R and closes at contact 204 the circuit for the yellow lamp Y and magnet 80 as described hereinbefore. Magnet 80 causes air pressure from cylinder 61 to enter pipe 120 leading to port 40 of cylinder 34, so that piston 36 is moved to the left against stop 41. Circuit controller 164^a or 164^b opens the stick circuit of relay 160, which therefore breaks the circuit for magnet 81 at contact 195. As a result pipe 121 is opened to atmosphere at valve 73 and the pressure in reservoir 124 and cylinder 34 gradually drops, so that the speed limit is gradually reduced from the high to the medium value and the yellow lamp Y is displayed. This process is repeated by the apparatus on each car of the train as the contact shoes of each car encounter the deenergized ramp 109 and the energized ramp 108, and as a result the speed limit is changed from the "high speed" to the "medium speed" on each car of the train in succession.

When the apparatus shown in Fig. 6 is employed on each car of a train, it is apparent that if the ramp 109 were located at the entrance of a block and were so controlled as to be deenergized upon the entrance of a train into the block, the first car or two of the train might receive a proceed indication from the ramp but the last cars would receive a stop indication owing to the deenergization of the ramp by the for-

ward part of the train, and the train would thus be brought to a stop even though traffic conditions were such that it could properly proceed at full speed. The control of the ramps must therefore be such that each ramp which is energized when encountered by a train continues to be energized until the entire train has passed over the ramp. One manner of securing such control is illustrated in Fig. 7, in which 1, 1' designate the track rails of a railroad track, one of which rails 1 is divided by means of insulated joints 111 into block sections N, O, P, etc., each of which is preceded by a preliminary section O', P', etc. Transformers T^o, T^p, etc., the secondary of each of which is divided into a number of sections a, b, c, d, are provided, one for each block, the primary of each transformer being connected with a source of alternating signaling current not shown in the drawing. Each track section is equipped with a track circuit. Thus the track circuit for section O consists of a source of electrical potential, which I have shown as section b of transformer T^p and is connected to the track rails by wires 261 and 263, the track rails 1 and 1', and a relay 251° which is connected to the rails 1 and 1' by means of wires 269 and 270. Similarly preliminary section O' is connected at one end to coil c of transformer T^o by wires 260 and 261 and is connected to a relay 250° by wires 267 and 268. Each block section is also provided with a line relay 252°, 252^p, etc., which has an energizing circuit and a holding circuit. The energizing circuit of relay 252°, for example, is: from section d of transformer T^o, through wire 265, contact 258 of relay 251°, wires 285 and 272, relay 252°, wires 271, 273 and 266 to transformer T^o. Hence relay 252° is picked up when relay 251° is energized. The stick circuit of relay 252° is as follows: from section d of transformer T^o, through wires 265 and 283, contact 256 of relay 252°, wire 284, back contact 255 of relay 250°, wire 272, relay 252°, wires 271, 273 and 266 to section d of transformer T^o. Therefore, relay 252° remains energized through its stick circuit, when relay 251° opens, provided back contact 255 of relay 250° has previously been closed. I provide, furthermore, other line relays 253°, 253^p, etc., one for each block section. Relay 253° may be energized through the circuit: from section d of transformer T^p, through wire 265, contact 258 of relay 251^p, wire 285, contact 254 of relay 250^p, wire 281, relay 253°, wires 280, 271, 273 and 266 to section d of transformer T^p. Hence relay 253° is energized if the front contacts of relay 250^p and 251^p are both closed. A ramp 109^a which may at times be energized is located in each auxiliary section O', P', etc. Ramp 109^a of section O' for

example may be energized through the connections, from section a of transformer T^o, through wire 262, contact 259 of relay 253°, wire 277, contact 257 of relay 252°, wire 278 to ramp 109^a. Hence this ramp rail is energized when both relays 252° and 253° are energized. 65 70

If a train equipped with the speed control apparatus described hereinbefore, meets an energized ramp 109^a, current flows from ramp 109^a through the apparatus on the train to rail 1' and from there by means of wire 261 back to section a of transformer T^o. 75

To describe the operation of this system of train control apparatus, assume no train 80 on the track. Then, referring particularly to block section O'—O, relays 250°, 251°, 252° and 253° are all energized. Ramp 109^a is energized because the front contacts of relays 252° and 253° are closed. If now a 85 train equipped with the speed control apparatus described hereinbefore, enters preliminary section O' from block section N it opens relay 250° which closes at back contact 255 the stick circuit of relay 252°. As 90 the train encounters ramp 109^a it receives a "proceed" indication in the cab due to the operation of the apparatus on the train or car, as described hereinbefore, and it may proceed under its high speed limit. Upon 95 entering section O, relay 251° is deenergized and breaks at contact 258 the pick-up circuit of relay 252°, but this relay does not open because its stick circuit is closed through back contact 255 of relay 250°. 100 Therefore ramp 109^a remains energized as long as any part of the train is in preliminary section O'. As the train leaves this preliminary section, relay 250° is again energized and opens at contact 255 the stick 105 circuit of relay 252°, which is therefore deenergized and opens at contact 257 the circuit for ramp 109^a. Therefore any following train upon entering preliminary section O' while section O is occupied will receive 110 a low speed indication. As the first mentioned train proceeds through section O and enters auxiliary section P' it deenergizes relay 250^p causing it to open at contact 254 the energizing circuit of relay 253°, which 115 therefore opens its contact 259. At ramp 109^a in auxiliary section P' the car or train receives a "proceed" indication and may therefore pass into section P at full speed. Relay 251^p is deenergized and opens at contact 258 the pick-up circuit of relay 252^p, but as explained hereinbefore relay 252^p remains energized through its stick circuit 120 closed at back contact 255 of relay 250^p. Hence ramp 109^a remains energized as long 125 as part of the train is in section P'. As it leaves section P' relay 250^p is energized and breaks at back contact 255 the stick circuit

of relay 252^P, which is therefore deenergized and breaks at contact 257 the connection of ramp 109^a to transformer T^P. Hence ramp 109^a is deenergized as soon as the rear of the 5 train is past.

When the train leaves block section P completely, relay 251^P is again energized and closes at contact 258 the circuit for relay 253° of the preceding section. Relay 252° 10 having already been energized as the train left section O, the circuit for ramp 109^a of section O' is again completed, so that if a following train makes contact with this ramp it will receive a "proceed" indication.

15 Thus the train is governed by the condition of the second block in advance provided the first block in advance is unoccupied at the time the train enters it, while if the train enters an occupied block, it is governed 20 solely by the condition of this block, irrespective of the condition of the block in advance of the occupied block. If two blocks ahead of the train are unoccupied a green light is displayed in the cab and the high 25 speed limit is applied, but if the second block ahead is occupied, a red light is displayed and the speed limit is gradually reduced to the low value at the entrance to the occupied block, which may be then entered 30 under control.

Fig. 8 shows a modification of the roadside apparatus described in Fig. 7 for use on curves and grades in the same way as Fig. 4 is a modification of the circuits of Fig. 3 for 35 the same purpose. The modification consists of the addition of ramps 108^a located between the tracks adjacent ramps 109^a. The ramps 108^a may be energized through the same circuits as ramps 109^a of Fig. 5, 40 but ramps 109^a have no electrical connections. By means of ramps 108^a the medium speed limit may be applied in the same way as described for Fig. 3.

The maximum traffic capacity is secured 45 when the roadside apparatus shown in Figs. 7 and 8 is used in connection with trains made up of several cars each of which is equipped with the control apparatus shown in Figs. 1 and 6 and which are connected 50 electrically by means of couplers 154, so that the train wires are connected in series throughout the length of the train. The length of the blocks is then preferably such that the distance between consecutive ramps 55 is less than the length of each train, so that the train is always in connection with one ramp. Assume that in Fig. 7 a train A occupies block P and that a following train B is about to enter preliminary section O'. 60 The first car of train B engages ramp 109^a causing a red light to be displayed in the cab, showing that block P is occupied, and deenergizing the "high speed" control so that the permissive speed will be reduced to 65 the low speed value before the train reaches

the entrance to block P. Suppose that before all of train B has passed ramp 109^a of block O' that train A leaves block P thereby reenergizing ramp 109^a of block O'. Since one of the cars of train B is in engagement with ramp 109^a, the control apparatus on that car is energized to re-apply the high speed limit, and at the same time train wire 152 is energized to simultaneously apply the high speed limit on all cars of the 75 train, displaying a green light in the cab of the first car, permitting full speed to be immediately resumed for the remainder of block O.

Assume that on the other hand the train 80 B had passed beyond ramp 109^a of block O' before train A leaves block P. Then if train A leaves block P the control apparatus on train B will be reenergized to apply the high speed control and to display the green light 85 when train B reaches ramp 109^b, which is preferably located near the exit end of block O and which is connected to ramp 109^a of block O' by wire 279. Thus the train B can now enter block P in the rear of an occupied 90 block under the same condition, namely, with the speed limit initially at the "high speed" value, as it previously entered the block O in the rear of the occupied block P. As train B enters blocks P, ramp 109^b becomes 95 deenergized, giving the same indication as ramp 109^a of block P', because track relay 251^P is deenergized, which opens the circuit of relay 253° at contact 258, and relay 253° opens the circuit of ramp 109^b at 100 contact 259.

Assume now that block P is unoccupied, so that ramp 109^a of block P' is energized, and that the train B entering block P is of sufficient length to engage ramp 109^b of 105 block O and ramp 109^a of block P' at the same time. Then the ramp 109^b as previously explained, will be deenergized because track relay 251^P is deenergized, but it will not affect the control of the train, which will 110 be controlled solely by the ramp 109^a of block P', because the relay 160 on the car in engagement with the deenergized ramp 109^b will be reenergized through train wire 152 from the relay 158 of the car in engagement with ramp 109^a, although its holding 115 circuit is temporarily broken by circuit controller 164^a or 164^b because of the engagement with ramp 109^a. Likewise if the train is of sufficient length to engage ramps 109^a and 109^b of block O' and O, and also ramp 109^a of block P' the energization of the latter is sufficient to enable the train to maintain full speed. Therefore two or more trains if 120 coupled together may operate as a unit because of train wires 151 and 152, while if not coupled together trains following the first train in the same block are held at the "low speed" limit.

Referring now to Fig. 9, I have here 130

shown a modification of the apparatus of Fig. 6. This modification differs from the apparatus of Fig. 6 in the following respects: Contact shoe 163 with its corresponding alternating current relay 159 and the medium speed control wire 153 of Fig. 6 are replaced by a contact 296 which is controlled by air pressure acting on one side of a diaphragm 295 in opposition to a spring 293 acting on a piston 294 on the other side of the diaphragm. Air pressure is brought to the underside of diaphragm 295 by means of a pipe 292 connected to the pipe 121 which is connected to port 39 of cylinder 34 in Fig. 1. When the pressure in pipe 121 is at or above a certain value predetermined by the adjustment of spring 293, contact 296 is closed due to the upward displacement of piston 294, but when the pressure falls below that value, contact 296 opens by action of the spring. The pick-up circuit of relay 161 is passed through contact 296, so that this circuit is as follows: from battery 155, through wires 156, 150, 197 and 298, contact 296, wire 297, relay 161, wires 192, 151 and 157 to battery 155. Hence the pick-up circuit of relay 161 is closed as long as air pressure above the predetermined value exists in pipe 121. The circuit for red light R is: from battery 155, through wires 156, 150, 197 and 299, back contact 196 of relay 160, wire 300, back contact 205 of relay 161, wire 200, lamp R, wires 192, 151 and 157 to battery 155. Hence red light R is displayed when both relays 160 and 161 are deenergized. The circuit for yellow light Y and magnet 80 is: from battery 155, through wires 156, 150, 197 and 299, back contact 196 of relay 160, wire 300, front contact 204 of relay 161, wire 215, lamp Y and winding 80^a of magnet 80 in multiple, wires 192, 151 and 157 to battery 155. Hence yellow light Y is displayed and magnet 80 is energized when relay 161 is energized and relay 160 is deenergized. The circuit for green light G and magnet 81 is: from battery 155, through wires 156, 150, 197 and 299, front contact 195 of relay 160, wire 202, lamp G and winding 81^a of magnet 81 in multiple, wires 192, 151 and 157 to battery 155. Hence when relay 160 is energized green light G is displayed and magnet 81 is energized.

When the apparatus shown in Fig. 9 is used in connection with that shown in Fig. 55 1, the tension of spring 37 in Fig. 1 is such that it exerts no pressure against diaphragm 341 unless piston 36 is forced to the left, because of air pressure in pipe 120, so that if the air pressure is exhausted from both pipes 120 and 121 the brakes will be applied automatically if the train is run at any speed. When the spring is compressed due to air pressure in pipe 120 the speed limit is increased to a low value, as for example 60 to 10 miles per hour. Since the high speed

limit is applied by the admission of air pressure through port 39 of cylinder 34, it remains the same as in the preceding cases.

To explain the operation of this modification of my system of train control, assume the apparatus is in the condition shown in Fig. 9, that is, that both relays 160 and 161 are energized. Then, as explained hereinbefore, green light G is displayed, magnet 81 is energized and, air pressure exists in pipe 121 and the adjoining passages, so that the high speed limit is applied. Assume now that the train reaches a deenergized ramp 109, so that the stick circuits of relays 160 and 161 are broken at contact 164^a or 164^b. Relay 160 is deenergized, but relay 161 remains energized, its circuit being closed at the pneumatically controlled contact 296. As a result, yellow light Y is displayed, magnet 80 is energized and magnet 81 is deenergized, so that the pressure in pipe 121 escapes through valve port 73 which is restricted in area so that the reduction of pressure is gradual. As the air pressure in pipe 121 gradually decreases, the speed limit is gradually reduced. Contact 296 opens as soon as the air pressure in pipe 121 drops below the predetermined value, but in the meantime the contact shoe has passed off the ramp 109 so that the stick circuit for relay 161 is closed through the shoe operated contact and this relay remains energized. Piston 36 is moved against stop 41 due to air pressure in pipe 120, compressing the spring 37, so that the train may proceed under the low speed limit of 10 miles per hour until a second ramp 109 is encountered. If this ramp is deenergized, the stick circuit of relay 161 is opened at contact 164^a or 164^b, and, contact 296 in the pick-up circuit of that relay being open, relay 161 is deenergized and opens at contact 204 the circuit for magnet 80 and yellow light Y. Air pressure is exhausted from pipe 120 removing the tension from spring 37. As explained hereinbefore, this causes the train to come to an absolute stop. Red light R is displayed, its circuit being closed at contact 205 of relay 161.

The train cannot proceed until it receives a "proceed" indication by the energization of the ramp 109 at which it came to a stop. If ramp 109 is energized, relay 158 is energized and closes the circuit for relay 160 at contact 189. Relay 160 closes at contact 195 the circuits of green light G and magnet 80. Therefore the green light G is displayed and air pressure is admitted to pipes 121 and 292, and contact 296 is again closed; thereupon relay 161 is energized and closes its contacts 202 and 204. Thus all the apparatus has been restored to the condition shown in Fig. 9, and the car or train may again proceed under the control of the "high speed" limit.

By this modification of my apparatus it

will be noted that I obtain the equivalent of the three indications, proceed, caution, and stop by means of two consecutive engagements with similar ramps which are only capable of transmitting either one of two possible indications to the train.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a centrifugal governor for operating controlling mechanism in one direction, and means for opposing the operation of said mechanism, said means comprising a diaphragm acted upon by spring pressure and air pressure and means to give said spring pressure a plurality of constant values.

2. In combination, a railway vehicle, a speed responsive device thereon, fluid pressure apparatus on the vehicle capable of assuming three fixed conditions in accordance with three fixed maximum speed limits, means on the vehicle controlled from the trackway for placing said apparatus in one or another of said conditions depending on traffic conditions in advance and for maintaining said apparatus in such condition until indication is received from the trackway of a change in traffic conditions in advance, and vehicle governing means controlled jointly by said device and said apparatus.

3. In combination, a railway vehicle, a speed responsive device thereon, two pistons, means for admitting fluid pressure behind one or the other of said pistons, and vehicle governing means controlled jointly by said device and said pistons.

4. In combination, means comprising a centrifugal governor for operating controlling mechanism in one direction, means for resisting the operating of said controlling mechanism by said governor, said means comprising means actuated by air pressure or spring pressure or both, and means for giving said spring pressure a plurality of values.

5. In combination, a shaft capable of reciprocal movement, a centrifugal governor, mechanism for transmitting the centrifugal force generated by the rotation of the governor to said shaft thereby tending to force said shaft in one direction, means adapted to be actuated by fluid pressure tending to force said shaft in the opposite direction, a spring for augmenting the force exerted by the fluid pressure on said shaft, means actuated by fluid pressure to change the force exerted on said shaft by said

spring, and means controlled by reciprocation of said shaft.

6. In combination, means capable of reciprocation, a spring, means responsive to fluid pressure and to said spring for holding the first-mentioned means in one extreme position, means controlled by fluid pressure for giving the force exerted by said spring a plurality of constant values, a centrifugal governor, mechanism for applying the force generated due to the rotation of said governor to the first-mentioned means in opposition to the force holding said means in one extreme position, and means controlled by the reciprocation of said first-mentioned means.

7. In combination, a shaft capable of reciprocation, stops for limiting the reciprocation of said shaft, a spring, a piston responsive to fluid pressure and to said spring for holding said shaft in one extreme position, a piston actuated by fluid pressure for compressing said spring, a centrifugal governor, mechanism for transmitting the force generated by the rotation of the governor to said shaft, so as to tend to force the shaft to its other extreme position, and means controlled by the reciprocation of said shaft.

8. In controlling apparatus for railway vehicles, a centrifuge operatively connected with an axle of the vehicle, means for opposing the centrifuge, said means being responsive to fluid pressure and spring pressure, means for giving said spring pressure a plurality of constant values, and means for controlling the vehicle when the centrifuge overcomes the first-mentioned means.

9. In combination, a railway vehicle, controlling means for said vehicle, a centrifugal governor adapted to rotate at a speed proportional to the speed of the vehicle, means for opposing the governor, said means being responsive to fluid pressure and spring pressure, means for giving said spring pressure a plurality of constant values, and means controlled by the centrifugal governor for controlling the controlling means for the vehicle.

10. In combination, a centrifugal governor, a piston, mechanism for transmitting the centrifugal force generated by the rotation of said governor to said piston, thereby tending to move said piston in one direction, a cylinder for said piston, another piston in said cylinder, a spring separating said two pistons, means for admitting air pressure behind said second piston, so that said spring is compressed, and means controlled by the first-mentioned piston.

11. In combination, a centrifugal governor, a piston, mechanism for transmitting the centrifugal force generated by the rotation of said governor to said piston, thereby tending to move said piston in one direction.

- tion, stops to limit the movement of said piston, a cylinder for said piston, a second piston in said cylinder, stops for limiting the movement of the second piston, a spring 5 separating said pistons, thereby opposing with one constant force the movement of the first-mentioned piston by the governor, means for admitting fluid pressure between said pistons so as to oppose the movement 10 of said piston by the governor with another constant or a variable force, means for admitting fluid pressure behind the second piston so as to compress the spring and oppose the movement of the first piston by 15 the governor with a third constant force, and means controlled by the first piston.
12. In combination, a centrifugal governor for forcing a piston movable between limits in one direction, a second piston movable between limits, a cylinder for the two pistons, a spring for normally separating said two pistons thereby opposing said governor with one constant force, means for admitting fluid pressure between said pistons thereby opposing said governor with 20 another constant or a variable force, means for admitting fluid pressure behind the second piston thereby moving said piston from one limit to the other so as to compress the 25 spring, thereby opposing the governor with a third constant force, and means controlled by the first mentioned piston.
13. In combination, a railway track, a vehicle adapted to travel thereon, means on 30 said vehicle for imposing a high speed limit, a medium speed limit and a low speed limit, high speed control ramp rails and medium speed control ramp rails adjacent said track and adapted to be energized, a high speed 35 control and a medium speed control electromagnet on the vehicle, the former adapted to be energized by current from the high speed control ramp rails and the latter adapted to be energized by the medium speed 40 control ramp rails; a slide valve adapted to control the first-mentioned means by assuming three positions, viz., a high speed control position, a medium speed control position and a low speed control position; means comprising a valve controlled 45 by the high speed control ramp rails, another valve controlled by the high speed control electromagnet and a cylinder with its position for controlling the high speed 50 control position of said slide valve, means comprising said ramp operated valve, another valve controlled by the medium speed control electromagnet and another cylinder with its piston for controlling the medium speed 55 control position of said slide valve, and means comprising said ramp operated valve, and a third piston with its cylinder for controlling the low speed control position of said slide valve.
14. In combination, a railway track, ramp 60 rails adjacent said track and adapted to be energized, a vehicle, a contact shoe on said vehicle adapted to engage with said ramp rails, an electromagnet on the vehicle, adapted to be energized by current from said ramp rails when engaged by the contact shoe, means on the vehicle for imposing a high speed and a low speed limit on the vehicle, a slide valve for controlling said means, a valve operated by the contact shoe, 65 means controlled by the electromagnet and said valve for controlling the position of said slide valve.
15. In combination, a railway track, ramp rails adjacent said track and adapted to be energized, a vehicle, a contact shoe on said vehicle adapted to engage said ramp rails, an electromagnet on the vehicle adapted to be energized from said ramp rails when engaged by the contact shoe, means on the 70 vehicle for imposing a plurality of speed limits on the vehicle, a slide valve for controlling said means, means for controlling said slide valve including said electromagnet and a valve operated by the ramp rails. 75
16. In combination, a railway track, ramp rails adjacent said track and adapted to be energized, a vehicle adapted to travel on said track, a centrifuge on said vehicle and adapted to rotate proportionally to the speed of the vehicle, means for opposing said centrifuge actuated by spring or air pressure, electro-pneumatic means controlled by said ramp rails for controlling said spring pressure and air pressure, and controlling apparatus on said vehicle controlled by the centrifuge. 80
17. In combination, a railway track, high speed control and medium speed control ramp rails adjacent said track and adapted to be energized, a vehicle adapted to travel on said track, a centrifuge operatively connected with an axle of the vehicle, means actuated by spring pressure or air pressure for opposing the centrifuge, means for controlling said spring pressure and air pressure, said means including a high speed control electromagnet, a medium speed control electromagnet, adapted to be energized by current from the high speed control ramp 85 rails and by current from the medium speed control electromagnets respectively, and a valve operated by said ramp rails, and means controlled by the centrifuge for limiting the speed of the vehicle to a high speed 90 limit, a medium speed limit or a low speed limit. 95
18. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 100
19. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 105
20. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 110
21. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 115
22. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 120
23. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 125
24. In combination, a railway track, a vehicle adapted to travel thereon, ramp rails adjacent said track and adapted to be energized, a centrifuge operatively connected with an axle of the vehicle, means actuated by spring pressure or air pressure for opposing the centrifuge, a slide valve for controlling said air pressure, said slide valve 130

being controlled by an electromagnet adapted to be energized by current from the ramp rails and a valve operated by said ramp rails, and controlling means on the vehicle 5 controlled by said centrifuge.

19. In combination, a railway track, ramp rails adjacent said track and adapted to be energized, a vehicle, a contact shoe on said vehicle adapted to engage said contact rails, 10 an electromagnet on the vehicle adapted to be energized from said ramp rails when engaged by the contact shoe, means on the vehicle for imposing a plurality of speed limits on the vehicle, a slide valve for controlling said means, said slide valve being adapted to assume a high speed, a low speed and a stop control position; means comprising a valve controlled by the ramp rails, another valve controlled by the electromagnet, and a cylinder and piston, for controlling the high speed position of said slide valve; means comprising said ram operated valve and a second cylinder and piston for controlling the stop position of said valve, 25 and means comprising a third cylinder and piston for arresting the slide valve in the low speed position as it travels from the high speed toward the stop position.

20. In combination, a centrifugal governor 30 operatively connected to the wheels of a vehicle for controlling speed controlling means of said vehicle, a spring for opposing said governor, means controlled by air pressure for controlling the force exerted by said spring, an electromagnet for controlling said air pressure, and means for controlling said electromagnet.

21. In combination, a railway vehicle, a speed responsive device thereon, means on 40 the vehicle for exerting a progressively varying force in opposition to said speed responsive device, means for arresting the variation of said force at an intermediate point, and vehicle governing means controlled by said speed responsive device and by said force-exerting means.

22. In combination, a railway vehicle, a centrifugal device thereon for imposing a high speed limit, a medium speed limit or 50 a low speed limit, fluid pressure means on the vehicle for selecting the speed limit to be imposed by said centrifugal device, electromagnets for controlling said fluid pressure selecting means, and trackway means 55 for controlling said electromagnets.

23. In combination, a railway vehicle, a speed responsive device thereon, apparatus also on the vehicle and coöperating with said device to impose three fixed speed limits, 60 and means on the vehicle controlled from the trackway for placing said apparatus in one or another of three predetermined conditions depending on traffic conditions in advance, and for maintaining said apparatus in such condition until indication is

received from the trackway of a change in traffic conditions in advance.

24. In combination, a railway vehicle, a speed responsive device thereon, means also on the vehicle and coöperating with said 70 device to impose three fixed speed limits, electromagnets on the vehicle for controlling said means to determine the speed limit to be imposed, and trackway means for controlling said electromagnets.

25. In combination, a railway vehicle, a speed responsive device thereon, fluid pressure means on the vehicle capable of assuming three fixed conditions in accordance with three fixed speed limits, electromagnets on the vehicle for controlling said fluid pressure means, trackway means for controlling said electromagnets, and vehicle governing means controlled jointly by said speed responsive device and said fluid pressure means.

26. In combination, a railway vehicle, a slide valve thereon capable of assuming high, medium and low speed positions, means located on the vehicle and controlled from the 90 trackway for determining the position of said valve in accordance with traffic conditions in advance, and vehicle governing means on the vehicle controlled by said valve for imposing a high, medium or low speed 95 limit according as said valve is in high, medium or low speed position.

27. In combination, a railway vehicle; a slide valve thereon capable of assuming a high speed position, a medium speed position and a low speed position, and biased to the latter position; means on the vehicle controlled by said valve for imposing a high, medium or low speed limit depending on the position of said valve; a high speed electromagnet and a low speed electromagnet on the vehicle; means comprising a valve controlled by the high speed magnet, and a cylinder and piston, for moving said slide valve to its high speed position when said high speed magnet is energized; means comprising another valve controlled by said medium speed magnet, and a cylinder and piston, for moving said slide valve to its medium speed position when the medium speed magnet is energized and the high speed magnet is deenergized; and trackway means for controlling said electromagnets.

28. In combination, a railway vehicle, a slide valve thereon capable of assuming a 120 high speed position, a medium speed position and a low speed position, and biased to the latter position; means on the vehicle controlled by said valve for imposing a high, medium or low speed limit depending on 125 the position of said valve; a high speed electromagnet and a low speed electromagnet on the vehicle; means controlled by said high speed magnet when energized for moving said slide valve to its high speed position, 130

means controlled by said medium speed magnet when energized for moving said slide valve to its medium speed position provided the high speed magnet is deenergized, and 5 trackway means for controlling said electromagnets.

29. In combination, a railway vehicle, means thereon for imposing a plurality of fixed speed limits, a slide valve on the vehicle for controlling said means, and means on the vehicle controlled from the trackway for determining the position of said slide valve in accordance with traffic conditions in advance.

15 30. In combination, a railway vehicle, means thereon including a slide valve for imposing a plurality of fixed speed limits according as said valve occupies one or another of a plurality of predetermined positions, and means on the vehicle controlled from the trackway for placing said valve in one or another of said positions depending on traffic conditions in advance and for maintaining said valve in such position until indication is received from the trackway of a change in traffic conditions in advance.

31. In combination, a railway vehicle, a speed responsive device thereon, means, also on the vehicle and coöperating with said device to impose a plurality of fixed speed limits, a slide valve for controlling said means, and means on the vehicle controlled from the trackway for placing said slide valve in one or another of a plurality of predetermined positions depending on traffic conditions in advance and for maintaining said valve in such position until indication is received from the trackway of a change in traffic conditions in advance.

40 32. In combination, a railway vehicle, a speed responsive device thereon, means also on the vehicle and coöperating with said device to impose a plurality of fixed speed limits, a slide valve on the vehicle for controlling said means, fluid pressure controlled

45 pistons for determining the position of said slide valve, means including electromagnets for controlling the supply of fluid pressure to said pistons, and trackway means for controlling said electromagnets.

50 33. In combination, a railway vehicle, a centrifugal device thereon operatively connected with a wheel of the vehicle, means on the vehicle for opposing the action of said device by a plurality of forces of different fixed amounts, vehicle governing means controlled by said centrifugal device and set into operation when the device overbalances the opposing force, and trackway

55 means for determining the force exerted on the centrifugal device by said means.

34. In combination, a railway vehicle, a centrifugal device thereon operatively connected with a wheel of the vehicle, means 60 on the vehicle for opposing the action of

said device by a plurality of forces of different fixed amounts, a slide valve for selecting the opposing force exerted by said means, fluid pressure controlled pistons for determining the position of said slide valve, 70 and means controlled from the trackway for governing the application of fluid pressure to said pistons.

35. In combination, a railway vehicle, a centrifugal device thereon operatively connected with a wheel of the vehicle, fluid pressure controlled means on the vehicle for opposing the action of said centrifugal device by three forces of different fixed amounts, a three position slide valve controlling the application of fluid pressure to said means, two electromagnets on the vehicle; means controlled by said magnets for moving said slide valve to one position when one magnet is energized, to the second position when the other magnet is energized and to the third position when both magnets are deenergized; vehicle governing means controlled by said centrifugal device and set into operation when the device overbalances 80 the opposing force, and trackway means for controlling said electromagnets.

36. In combination, a railway vehicle, fluid pressure apparatus thereon capable of assuming three fixed conditions corresponding to three fixed speed limits, a speed responsive device on the vehicle coöperating with said apparatus to cause a brake application when the speed at any time exceeds the speed limit corresponding to the condition of said apparatus at such time, and means on the vehicle controlled from the trackway for placing said apparatus in one or another of said conditions depending on traffic conditions in advance and for maintaining said apparatus in such condition until indication is received from the trackway of a change in traffic conditions in advance.

37. In a train speed control apparatus, 110 the combination with a mechanism for effecting an increase and a decrease in the speed limit of the train of high and low speed contact sections located along the track and electrically controlled means on the 115 train operated upon passing an energized high speed contact section for effecting the operation of said mechanism to increase the maximum speed limit of the train and operated upon passing a deenergized low speed 120 contact section for effecting the operation of said mechanism to reduce the maximum speed limit of the train.

38. In a train speed control apparatus, the combination with a device governed by 125 the speed of the train for limiting the speed thereof, of a valve device operated upon a predetermined reduction in fluid pressure for effecting the adjustment of said device to reduce the operating speed limit of said 130

device, normally energized contacts located along the track, and an electrically controlled means on the train operated upon passing an energized contact for supplying fluid to said valve device to prevent the operation thereof.

39. In a train speed control apparatus, the combination with a train speed controlled mechanism, electrically controlled means for adjusting said mechanism to operate at a higher speed limit, and electrically controlled means for adjusting said mechanism to operate at a minimum speed limit, of contacts
- 10

located along the track, the energization of which is adapted to effect the operation of 15 the high speed electrically controlled means, and other contacts adapted upon deenergization to effect the operation of the minimum speed electrically controlled means.

In testimony whereof I affix my signature 20 in presence of two witnesses.

LLOYD V. LEWIS.
